UNITED STATES PATENT OFFICE.

DALLETH Z. MERCHANT, OF PORTSMOUTH, VIRGINIA.

DESIGN FOR A BADGE.

No. 38,017.

Specification for Design.

Patented May 22, 1906.

Application filed March 23, 1906. Serial No. 307,726. Term of patent 3½ years.

To all whom it may concern:

Be it known that I, DALLETH Z. MERCHANT, a citizen of the United States, residing at Portsmouth, in the county of Norfolk and State of Virginia, have invented a new, original, and ornamental Design for Badges, of which the following is a specification, reference being had to the accompanying drawings, forming a part thereof.

My invention relates to badges.

The drawing shows a plan view.

I claim—

The ornamental design for a badge as shown.

DALLETH Z. MERCHANT.
